(57) **CLAIM**

The ornamental design for a humidification module for a patient interface, as shown and described.

DESCRIPTION

FIG. 1 is a rear perspective view of a humidification module for patient interface showing our new design according to a first embodiment;

FIG. 2 is an enlarged front perspective view thereof shown in isolation;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is yet another rear perspective view thereof;

FIG. 10 is a rear perspective view of a humidification module for patient interface showing our new design according to a second embodiment;

FIG. 11 is an enlarged front perspective view thereof shown in isolation;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof; and,

FIG. 18 is yet another rear perspective view thereof.

One or more views (e.g., bottom view) may not be shown as those views are unornamented or simply not claimed in a given embodiment.

The broken lines in FIGS. 1 and 10 illustrate environmental structure, all other broken lines illustrate portions of the humidification module for a patient interface; all broken lines form no part of the claimed design.

(Continued)

The combination of line shading, if any, is intended to convey a contrast in appearance/materials.
